UNITED STATES PATENT OFFICE.

GEORGE PATERSON, OF BARRE, VERMONT.

WRENCH.

No. 902,759.

Specification of Letters Patent.

Patented Nov. 3, 1908.

Application filed June 15, 1908. Serial No. 438,561.

To all whom it may concern:

Be it known that I, GEORGE PATERSON, a citizen of the United States, residing at Barre, in the county of Washington and State of Vermont, have invented certain new and useful Improvements in Pipe-Wrenches; and I do declare the following to be a full, clear, and exact description of the invention, such as will enable others skilled in the art 10 to which it appertains to make and use the same.

This invention relates to improvements in pipe wrenches.

The object of the invention is to provide 15 a pipe wrench, the jaws of which are operated by a proper manipulation of the handle to engage and disengage them from the objects to be turned, and by means of which the pressure applied to the handle in one direction will serve to firmly grip both jaws 20 with the object to be turned.

With this and other objects in view, the invention consists of certain novel features of construction, combination and arrangement 25 of parts as will be described and particularly pointed out in the appended claims.

In the accompanying drawing, Figure 1 is a side view of a wrench showing the jaws in closed position; Fig. 2 is a similar view 30 showing the jaws in open position; Fig. 3 is a front view with the parts as shown in Fig. 1; and Fig. 4 is a detail perspective view of the inner and outer jaw members, and the upper end of the handle showing these parts 35 disconnected.

Referring more particularly to the drawings, 1 denotes the handle, which is here shown in the form of a flat metal bar having a rearwardly curved bifurcated upper 40 end, 2. In the bifurcated upper end of the handle, is pivotally connected the lower end or shank, 3, of the outer jaw, 4, said jaw having a serrated gripping or engaging surface, 5, and beveled outer edges.

45 The inner jaw 6 is provided with a shank in the form of spaced parallel plates, 7, the inner ends of which are pivotally connected to the handle, 1, below the bifurcated end 2 of the same. The upper and lower ends of 50 the parallel side plates 7 of the inner jaw are offset as shown at 8, so that said ends may be brought into close engagement with the handle below the end 2, and with the shank 3 of the outer jaw, as shown. In the plates 55 7, adjacent to their outer ends is arranged a transverse pin, 9, which is engaged with a

curved slot, 10, formed in the shank 3 of the outer jaw, as shown.

The shank, 3, of the outer jaw is curved rearwardly to engage the rearwardly curved bifurcated upper end of the handle whereby 60 said outer jaw is operated in the proper manner to cause the same to be engaged with and disengaged from the object to be turned when the handle is swung in one direction or 65 the other. The shank, 3, is reduced or of less width than the jaw, 4, thus providing shoulders 12 on the opposite sides of the jaw, 4, said shoulders being formed on a curve or 70 are to correspond with the curve or rounded rear upper corner of the inner jaw.

Secured to the lower side of the inner jaw, adjacent to the forward edge of the shank plates, 7, is a spring, 13, which may be of 75 any suitable construction, but which is here shown and is preferably in the form of a bail, the ends of which are secured to the jaw, as shown, while the lower looped portion of the same is adapted to bear against the forward side of the bifurcated upper end 80 of the handle, the tension of the spring being exerted to aid in forcing said bifurcated upper end of the handle and the shank of the outer jaw rearwardly between the side plates 7 of the shank of the inner jaw, thus 85 causing the outer jaw to move inwardly toward the inner jaw.

In using the wrench, the lower end of the handle is swung backwardly or rearwardly, which will cause the bifurcated upper end 90 of the same and the shank 3 of the outer jaw to move forwardly, thereby opening the jaws to the proper extent for engaging the object to be turned. After the jaws have thus been opened and engaged with the object, the handle is swung or forced forwardly 95 in the opposite direction, thus causing both the outer and inner jaws to firmly grip the object. By thus arranging the jaws and connecting the same to the handle, the more 100 pressure applied to the latter, the tighter the jaws will be gripped on the object to be turned.

From the foregoing description, taken in connection with the accompanying drawing, 105 the construction and operation of the invention will be readily understood without requiring a more extended explanation.

Various changes in the form, proportion and the minor details of construction may be 110 resorted to without departing from the principle or sacrificing any of the advantages

of the invention as defined in the appended claims.

Having thus described my invention, what I claim as new and desire to secure by Letters-Patent, is:

1. In a pipe wrench, a handle having a rearwardly curved bifurcated upper end, an outer jaw having a reduced rearwardly curved shank pivotally connected in the bifurcated upper end of said handle, an inner jaw having a shank formed of parallel plates adapted to engage the shank of said outer jaw and the upper end of the handle, means to pivotally connect the lower end of said plates with the handle, a pin and slot connection between the shanks of said inner and outer jaws, and a jaw operating spring secured to the inner jaw and adapted to bear against the curved upper end of the handle, substantially as described.
2. In a pipe wrench a handle having a rearwardly curved bifurcated upper end, an inner jaw having a shank formed of parallel

plates offset intermediate their ends to provide a space to receive the bifurcated upper end of said handle, said plates having a pivotal connection at their lower end with the handle below said bifurcated upper end, an outer jaw having a reduced rearwardly curved shank arranged between the upper ends of said inner jaw shank plates, said outer jaw having a pivoted sliding engagement with said plates, and a pivotal connection with the bifurcated upper end of said handle, and a spring secured at one end to said outer jaw shank and having its opposite end bearing against the upper end of said handle whereby the operation of said jaws is facilitated.

In testimony whereof I have hereunto set my hand in presence of two subscribing witnesses.

GEORGE PATERSON.
